UNITED STATES PATENT OFFICE.

ELMER W. LINCOLN, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

Application filed September 16, 1922. Serial No. 588,549.

My invention relates to telephone system in which manual link or cord circuits are provided for interconnecting telephone lines, and has to do more particularly with systems in which instantaneous automatic ringing, listening, secret service, peg count and instantaneous disconnect and recall are provided.

In cord circuits provided with the above-mentioned features, prior to my invention, and where only one subscriber's line is automatically disconnected from the cord circuit, eight or more relays are required, and where both subscribers' lines are disconnected from the cord circuit, nine or more relays are required in the cord circuit to effect a positive operation of the system possessing said features, and it is the object of my invention to reduce the number of relays where single link disconnection is provided to six relays, and to reduce the number of relays where double link disconnection is provided to eight relays.

Another feature of my invention is the provision of means whereby the calling and called subscribers' lines are both automatically disconnected from the cord circuit interconnecting said lines when both subscribers have replaced their receivers upon their respective switchhooks, but neither of said subscribers' lines will be disconnected so long as the other subscriber's receiver remains off its switchhook.

Still another feature of my invention is the provision of means in the cord circuit whereby the cord circuit may be used for signaling a called subscriber whose substation is on the same line with the calling subscriber's substation, and also for indicating to the operator when the subscribers have replaced their receivers after conversation.

The above features, as well as others, will be more fully hereinafter described in the following specification.

For a more complete and better understanding of my invention, reference may be had to the accompanying drawings, Figs. 1 and 2, in which I illustrate my invention operating in connection with a telephone system. The system in Fig. 1 is provided with link disconnect means at both ends for disconnecting both the calling and called subscribers' lines from the link circuit, while in Fig. 2 means are provided for only disconnecting the calling subscriber's line.

In Fig. 1 of the drawing I show a calling substation A and a called substation B, the said calling and called substations A and B terminating, respectively, at the exchange in line circuits L and L'. The line circuits L and L' at the exchange comprise, respectively, the usual line relays LR and LR', cut-off relays CO and CO', multiple jacks MJ and MJ', and the multiple line lamp signals S and S'. The jacks of the lines are distributed among different operators and there is a line signal for each jack at the operator's position so that when a call is initiated over the line the line signals at the operator's positions are lighted, and one of a plurality of operators may seize the call to the exclusion of the other operators.

The cord circuit C for interconnecting the substations A and B as calling and called lines is provided with an answering plug AP and a calling plug CP, the said answering and calling plugs AP and CP being connected by the heavily marked conductors having the condensers K and K' interposed. The answering end of the cord has a combined sleeve and link disconnect relay SLR, which is energized when the plug AP is inserted into a jack MJ and de-energized when the calling and called subscribers have both replaced their receivers upon their respective switchhooks. Said relay de-energizing disassociates the cord C from the line circuit L, thereby permitting the calling subscriber to again resume control of the line circuit L to enable him to initiate another call, regardless of whether or not the plug AP has been removed from the jack MJ. An answering supervisory relay AS is provided which is energized over the calling subscriber's line and which relay, when energized, closes an energizing circuit for the operator's relay OR and the answering meter magnet AM. Relay OR operates to connect the operator's telephone set to the cord circuit C, and magnet AM operates to register the number of calls answered by the operator. A guarding relay GR and a high resistance relay HR are also provided for purposes to be hereinafter pointed out.

The calling end of the cord circuit C is provided with a combined sleeve and link disconnect relay SLR' which energizes when the calling plug CP is inserted into the multiple jack MJ' and the relay GR is in its de-energized position. An interrupter

ringing relay IR is provided which is energized when the operator depresses the ringing key RK to connect one of the ringing generators G, G', G² and G³ to the called subscriber's line. A ringing control relay RC is provided which energizes when the ringing key RK is fully depressed to connect an interrupter device I in circuit with the upper winding of the interrupter relay 10 whereby relay IR is caused to be intermittently operated to connect ringing current to the called subscriber's line. A supervisory lamp SL is provided which lights as soon as the calling plug CP is inserted into the multiple jack MJ' and remains lighted until the operator depresses the ringing key RK; the burning lamp SL thus serving as a signal to notify the operator that ringing current has not been connected to the called 20 line. The lamp SL will also light when both subscribers have replaced their receivers upon their respective switchhooks to notify the operator that disconnection is desired.

Referring now to the guarding relay GR, this relay energizes when both the calling and called subscribers have replaced their receivers upon their respective switchhooks. Relay HR will also energize to provide a holding circuit for relay GR. Relay GR energizing opens the holding circuit of the relay SLR, which relay SLR will de-energize to dissociate the answering end of the cord circuit C from the multiple jack MJ, thereby freeing the calling subscriber's 30 line and line circuit L. Relay GR energizing also opens the holding circuit of relay SLR', which will cause relay SLR' to de-energize to dissociate the cord circuit C from the multiple jack MJ', thereby freeing the called subscriber's line and line circuit L'. Should the calling subscriber replace his receiver upon its switchhook before the called subscriber responds, relay GR will energize to open the holding circuit of relay 40 SLR and the holding circuit of relay SLR'; thus automatically disconnecting ringing current from the cord circuit C and also freeing the calling and called subscribers' lines from the cord circuit C.

Referring now in general to the system in Fig. 2, which is a modification of the system illustrated in Fig. 1, it comprises a calling and called substation D and E, terminating in line circuits L² and L³, respectively, said line circuits being arranged identically the same as line circuits L and L' in Fig. 1. The cord circuit C' is provided with an answering plug AP' and a calling plug CP', which are interconnected by the heavily marked conductors having the condensers K² and K³ interposed. The answering end of the cord circuit C' is provided with a combined sleeve and link disconnect relay SLR², which energizes when the plug AP' is inserted into a multiple 50 jack MJ². Relay SLR² energizing closes a circuit for relay AR', which relay AR' operates to close a circuit for the answering meter relay AM', which in turn energizes to close a circuit for the relay MR', which 70 relay MR' operates to register the number of calls answered by the operator. A relay OR' is provided for automatically connecting the operator's telephone set to the cord circuit when the plug AP' has been inserted 75 into a multiple jack MJ² and relay SLR² has operated.

The calling end of the cord circuit C' is provided with a calling sleeve relay CSR which energizes when the calling plug CP' is inserted into a multiple jack MJ³. A ringing interrupter relay IR' is provided and operates when the ringing key RK' is depressed to connect one of the generators G⁴, G⁵, G⁶ or G⁷ to the called line to signal 85 the called subscriber thereon. A slow-acting ringing control relay RC' is provided which energizes when the ringing key RK' is operated to connect an interrupter device 90 in circuit with the interrupter relay IR', thereby causing ringing current to be intermittently applied to the called subscriber's line. Relay RC' remains energized so long as the plugs AP' and CP' are connected 95 to the multiple jacks and the calling subscriber's receiver is removed from its switchhook and the called subscriber's receiver remains on its switchhook. A supervisory lamp SL' is provided which lights as soon as the plug CP' is inserted into a multiple 100 jack MJ³, and remains burning until the ringing key RK' is operated to connect ringing current to the called subscriber's line, said lamp serving as a signal to notify the operator whether or not ringing current has 105 been connected to the called line. Lamp SL' will also burn when conversation has terminated and both subscribers hang up their receivers to indicate that connection is no longer desired.

Referring now more in detail to the operation of my invention, I will first describe in detail the operation of the system illustrated in Fig. 1. Assuming that the subscriber at the substation A desires to converse with the subscriber at the substation B, he will remove his receiver from its switchhook, thus closing a circuit for the line relay LR, traced from battery, winding of relay LR, normal contact 1 of cut-off relay CO, line limb 3, the now closed switchhook contacts of substation A, line limb 4, normal contact 2 of cut-off relay CO to ground. Relay LR energizing closes its normally open contact 5, thereby closing a circuit from battery, through the lamps S and to ground through the now closed contact 5 of relay LR. The lamps S will be lighted over this circuit at a plurality of operators' positions. Assuming that it is the operator at cord circuit C that answers 110

the call, the insertion of the answering plug AP into the jack MJ of the calling line establishes a series energizing circuit for the cut-off relay CO of the line circuit L and 5 the combined sleeve and link disconnect relay SLR, the circuit being traced from battery through the windings 6 and 7 of relay SLR, normal contact 8 of relay GR, conductor 9, sleeve contacts of the plug AP and 10 jack MJ, to ground through the winding of cut-off relay CO. The closure of alternate contact 10 of relay SLR, upon its energization, closes a lower resistance circuit through its winding 6, this circuit being traced from 15 battery through the upper winding 6 of relay SLR, its alternate contact 10, and over the previously traced circuit, relay AS having energized upon the energization of relay SLR over a circuit traced from battery, 20 through the lower winding of relay AS, alternate contact 11 of relay SLR, ring contacts of plug AP and jack MJ, through the substation A, tip contacts of jack MJ and plug AP, alternate contact 12 of relay SLR, 25 to ground through the upper winding of relay AS. The high resistance winding 7 of the relay SLR is shunted, this arrangement providing for secret service, as a relay SLR of a second cord circuit will not operate 30 in series with the relay CO as the shunt of the low resistance winding 6 of the relay SLR of the first cord circuit renders the relay SLR of the second cord circuit inoperative. The operation of relay CO causes relay LR to restore, thereby causing the effacement of the lamp signals S. Relay AS energizing closes a circuit for the operator's relay OR, which energizes to connect the operator's telephone set in circuit with the calling subscriber's line, said circuit being traced from battery, through the winding of relay OR, conductor 13, alternate contact 14 of relay AR, conductor 15, to ground through normal contact 16 of relay SLR'. 40 Relay AR also closes a circuit for the answering meter magnet AM, which energizes to operate the registering device to register the number of calls answered by the operator. The circuit for magnet AM may be traced from battery, winding of magnet AM, alternate contact 14 of relay AS, conductor 15, normal contact 16 of relay SLR', to ground. 45 The operator's set O now being connected in circuit with the subscriber at the calling substation A, she will inquire the wants of said subscriber, and assuming that he desires to converse with the subscriber at substation B, the operator will make the usual test to determine the busy or idle condition of the called subscriber's line in the well-known manner; and assuming that the line is found to be idle, the operator will insert the calling plug CP into the jack MJ', thereby bringing about the operation of re- 50 lay SLR' and the cut-off relay CO' in series, the circuit for said relays being traced from battery, through the winding of said relay SLR', conductor 18, normal contact 19 of relay GR, conductor 20, sleeve contacts 70 of relay CP and jack MJ', to ground through the winding of the cut-off relay CO'. Relay CO' operating removes the line relay LR' from the control of the called subscriber B so that when the called subscriber answers, the lamps S' will not light. Relay SLR' energizing opens the energizing circuit of relays OR and AM at normal contact 16, thereby disconnecting the operator's set from the cord circuit C to provide 80 secret service and to prevent the further operation of the registering device. The operator will now depress the proper ringing key plunger of the party-line ringing key RK to its fully depressed position to 85 close the end spring contact 21 and to connect the proper ringing generator G, G', G² or G³ to signal the called-for subscriber at substation B. The closing of alternate contact 21 of the end springs brings about 90 the energization of the interrupter relay IR, during the interval of that the key is held down, over a circuit traced from battery, through the upper winding of relay IR, alternate contact 21 of the end spring, conductors 25 and 43, to ground through alternate contact 16 of relay SLR'. The closing of alternate contact 24 of relay IR connects ringing current from the generator 95 G³, which we will assume is the generator 100 selected to ring the call bell of the subscriber at substation B, giving an instantaneous first ring to the called subscriber's bell. The closing of alternate contact 22 of the end spring of the key plunger closes 105 a circuit for ringing control relay RC, traced from battery, winding of relay RC, alternate contact 22 of the end spring, conductors 25 and 43, though alternate contact 16 of relay SLR' to ground. Relay RC energizing over this circuit establishes a locking circuit for itself, traced from battery through the winding of said relay RC, its alternate contact 27, conductor 28, normal contact 29 of relay GR, conductor 30, normal contact 23 of relay CR, conductor 43, alternate contact 16 of relay SLR', to ground. The opening of normal contact 110 31 of relay RC effaces the supervisory signal SL. The closing of alternate contact 120 32 of relay RC connects the interrupter I to the lower winding of interrupter relay IR, the circuit being traced from battery, through the lower winding of relay IR, alternate contact 32 of relay RC, to ground 125 through the constantly rotating interrupter device I. The relay IR is thus intermittently energized and de-energized to connect ringing current from generator G³ 130 to the called line over a circuit traced from

the ungrounded pole of the generator G³, to conductor 90, alternate contact 24 of the relay IR, conductor 91, alternate contact 92, of relay SLR', tip contacts of the connected plug CP and jack MJ' through the call bell and condenser at called substation B, back through the ring contacts of the jack MJ' and plug CP, alternate contact 93 of relay SLR', conductor 94 to ground 10 at alternate contact 95 of relay IR.

The closing of alternate contact 34 of relay IR transmits a ringing tone to the calling subscriber at substation A, the ringing tone being traced from the ground through 15 the generator G, over conductor 36, alternate contact 34 of relay IR, alternate contact 12 of relay SLR, tip contacts of plug AP and jack MJ, through the receiver at substation A, ring contacts of jack MJ and 20 plug AP, alternate contact 11 of relay SLR, lower winding of relay AS to battery, giving the calling subscriber at substation A an audible signal notifying him that the called subscriber at substation B is being signaled. 25 The called subscriber at the substation B is thus automatically signaled until he answers in response to his call signal or until the calling subscriber replaces his receiver before the said called subscriber answers. 30

Should the calling subscriber replace his receiver before the called subscriber answers, the answering relay AS will restore, due to the interrupted switchbook contacts at the 35 calling substation A. The closing of normal contact 38 of relay AS closes an energizing circuit for relay GR, traced from battery through the winding of said relay GR, normal contact 39 of relay CR, conductor 40, normal contact 38 of relay AS, alternate contact 41 of relay SLR, conductors 42 and 43 to ground at alternate contact 16 of relay SLR'. Relay GR energizing opens its normally closed make-before-break contact 45 19, thereby opening the circuit of relay SLR', whereby said relay restores, and also closes a circuit for the high resistance relay HR, which will operate to close a holding circuit for relay GR, traced from battery, winding of relay GR to ground at alternate contact 45 of relay HR, the circuit for relay HR being traced from battery, winding of said relay HR, alternate contact 19 of relay GR, conductor 20, sleeve contacts of plug CP and jack MJ' to ground through the winding of cut-off relay CO'. Relay CO' will not operate over this circuit due to the high resistance of relay HR, nor will the line test busy, since the potential upon the jack MJ' will not be sufficient to energize the test relay TR in the operator's circuit. Relay GR upon energizing opens its normal contact 8, thereby opening the holding circuit of relay SLR. Relays SLR and SLR'

restoring disassociate the cord circuit C from 65 the calling and called subscribers' lines, respectively, and relay GR energizing opens the circuit of ringing control relay RC at its normal contact 29, whereupon relay RC restores to bring about the disconnection of 70 ringing current from the cord circuit C. The calling and called subscribers' lines are now free and either subscriber may initiate a call or be called, as the case may be. 75

Assuming, however, that the calling subscriber does not replace his receiver and that the called subscriber at substation B removes his receiver during a silent or non-ringing period, that is, when relay IR is in its de-energized position, a circuit will be closed 80 for the relay CR over a circuit traced from battery, through the lower winding of relay CR, normal contact 95 of relay IR, alternate contact 93 of relay SLR', ring contacts of plug CP and jack MJ', through the now 85 closed switchhook contacts of substation B, tip contacts of jack MJ' and plug CP, alternate contact 92 of relay SLR', normal contact 24 of relay IR, upper winding of relay CR to ground. Relay CR will not energize 90 when in series circuit with the call bell and condenser at the called substation B, due to the combined high resistances of said call bell and condenser. Relay CR having energized over the above traced circuit opens the 95 locking circuit of the ringing control relay RC at its normally closed contact 23, which causes relay RC to restore to close its normal contacts 47 and 50 in the talking conductors of the cord circuit C, and to open 100 its alternate contact 32, thereby opening the circuit through the upper winding of relay IR to prevent the further operation of relay IR and the application of ringing current to the called line. 105

The called and calling subscribers at the substations A and B are now in conversational circuit, the talking circuit being traced over the heavily marked conductors. After the subscribers have finished conversation, they replace their receivers upon their respective switchhooks, causing the relays AS and CR to restore, due to the opening 110 of the switchhook contacts at the respective substations. Said relays restoring close their normal contacts 38 and 39, thereby closing a circuit for relay GR, the circuit being the same as has already been traced. Relay GR energizing, relay HR will energize, and relays SLR and SLR' will de-energize to 115 disassociate the cord circuit C from the subscribers' lines. Lamp signal SL will light over a circuit traced from battery, through the lamp SL, normal contact 31 of relay RC, conductor 30 to ground at alternate contact 29 of relay GR, to notify the operator that conversation has terminated. The operator 120 will now withdraw the plugs AP and CP 125

from the jacks MJ and MJ', whereupon relays GR and HR will restore to normal and the cord circuit will be in readiness for another connection.

5 Reverting now to when the operator tested the called line, and should the called subscriber's line be busy either as a calling or a called line, there will be a battery potential upon the sleeve contact of the multiple 10 jack MJ' so that when the operator touches the tip of the calling plug CP to said sleeve contact, a circuit will be closed for the busy test relay TR, traced from battery at the sleeve of said multiple jack MJ', tip contact of plug CP, normal contact 70 of relay SLR', conductor 71, to ground through the winding of the test relay TR. Relay TR energizing over this circuit closes its alternate contact 72, which closes a circuit 15 through the tertiary winding of the operator's set O to give her the usual well-known click in the ear to notify her that the line is busy, said circuit being traced from battery through the winding of coil 73, alternate contact 72 of relay TR to ground. Relay TR will only operate to give a busy signal when the called line is actually busy and in conversational circuit, but will not operate when the high resistance relay HR of a 20 cord circuit connected to the called line has operated after the termination of conversation, for in this instance the battery potential upon the sleeve contact of the jack MJ' from the relay HR is not sufficiently strong 25 to operate the test relay TR in the operator's circuit.

Assuming now that the calling subscriber desired to talk with a subscriber SS who is on the same line with said calling subscriber 40 but only indicated on the drawing by lines 3' and 4' which are tied to line conductors 3 and 4 respectively and lead to the substation of the subscriber SS, the said substation being identical in construction and 45 operation as substation A, the operator will answer the call in the same manner as before described, and upon learning that the subscriber wanted is on the same line with the calling subscriber, she will notify the 50 calling subscriber of this fact and will tell him to hang up his receiver while she rings the called-for subscriber. The operator will withdraw the answering plug AP from the jack MJ and will insert the calling plug 55 CP into the jack MJ, thereby closing a circuit for relay SLR', traced from battery, through the winding of said relay SLR', conductor 18, make-before-break contact 19 of relay GR, conductor 20, sleeve contacts 60 of plug CP and jack MJ to ground through the cut-off relay CO. Relay SLR' energizing closes a circuit for the lamp SL, which will burn until the operator depresses the ringing key plunger of ringing 65 key RK, said circuit being traced from bat-

tery through lamp SL, normal contact 31 of relay RC, normal contact 23 of relay CR, conductor 43 and to ground at alternate contact 16 of relay SLR'. The burning of lamp SL at this time will notify the operator that the ringing key has not been operated, and she will then operate the proper ringing key plunger of the ringing key RK to connect the proper frequency generator, which we will assume is the generator G², 70 to ring the called-for subscriber. When the key plunger is in its fully depressed position, alternate contact 21 of the end spring is closed to establish a circuit for the interrupter relay IR, traced from battery, 75 through the upper winding of relay IR, alternate contact 21 of the end springs, conductors 25 and 43, to ground at alternate contact 16 of relay SLR'. Ringing control relay RC will also energize when the 80 key plunger is fully depressed, over a circuit traced from battery, through the winding of said relay RC, alternate contact 22 of the key plunger, conductors 25 and 43 and to ground at alternate contact 16 of 85 relay SLR'. Said relay RC energizing will close a locking circuit for itself traced from battery, through the winding of said relay RC, its alternate contact 27, conductor 28, normal contact 29 of relay GR, conductor 90 30, normal contact 23 of relay CR, conductor 43 to ground at alternate contact 16 of relay SLR'. Relay RC operating opens the circuit of the lamp signal SL at its normal contact 31, and closes its alternate contact 95 32 to connect the interrupter device I in circuit with the lower winding of relay IR. Relay IR will intermittently energize and de-energize to intermittently ring the called subscriber. When the called subscriber 100 answers and the relay IR is in its de-energized position, a circuit is closed for relay CR including the now closed contacts of switchhook at the called subscriber's substation. Said relay CR operating opens 110 the circuit of relay RC at normal contact 23 of relay CR, whereupon relays RC and IR restore to prevent further application of ringing current to the called substation. After a reasonable time has elapsed the 115 calling subscriber removes his receiver and the two subscribers are now able to converse with each other.

After conversation has terminated, the subscribers replace their receivers upon 120 their respective switchhooks, thus opening the circuit of relay CR at the switchhook contacts, and relay CR restoring closes a circuit for the lamp SL, which will now 125 light to indicate that the connection may be taken down, said circuit for the lamp SL being the same as before traced. The operator seeing the burning lamp will withdraw the plug CP from the jack MJ, whereupon relays SLR' and CO restore and the lamp 130

SL is effaced, thus rendering the cord circuit C available for another connection.

Operation of system illustrated in Fig. 2.

- 5 Assuming that the subscriber D removes his receiver from its switchhook to initiate a call, a circuit will be closed for the line relay LR², traced from battery, winding of relay LR², normal contact 101 of cut-off relay CO², line limb 102, through the substation D, line limb 103, to ground through normal contact 104 of relay CO². Relay LR² energizes, closing a circuit for the line lamps S², which lamps will light before a plurality of operators. Assuming that it is the operator at cord circuit C' that answers the call, the insertion of the plug AP' into the jack MJ² of the calling line establishes a series energizing a circuit for the combined sleeve and link disconnect relay SLR² and cut-off relay CO², said circuit being traced from battery, through both windings 105 and 106 of relay SLR², conductor 107, normal contact 108 of relay CSR, conductor 109, sleeve contacts of plug AP' and jack MJ² to ground through the winding of cut-off relay CO². Relay CO² operates over this circuit to open its normal contact 101, thereby opening the circuit of relay LR², which restores to cause the effacement of the lamp signals S². Relay SLR² energizing closes its alternate contacts 110, 111, 112, 113 and 114, said alternate contacts 110 and 114 closing a circuit for the relay AR', traced from battery, through the lower winding of the relay AR', alternate contact 114 of relay SLR², ring contacts of plug AP' and jack MJ², through the substation D, the contacts of jack MJ² and plug AP', alternate contact 110 of relay SLR², through the upper winding of relay AR' to ground. Relay AR' energizing closes its alternate contact 115 to close a holding circuit for relay SLR² and closes its alternate contact 116 to close a circuit for the answering meter relay AM', which will energize to close a circuit for relay MR' to cause the same to operate the call registering mechanism, whereby the number of calls answered by the operator at cord circuit C' is registered, the circuit for relay AM' being traced from battery, through the winding of relay AM', alternate contact 116 of relay AR', conductor 117, normal contact 118 of relay CSR to ground; and the circuit for relay MR' being from battery through the winding of relay MR', alternate contact 119 of relay AM' to ground.
- 60 The closure of alternate contact 112 of relay SLR² upon its energization closes a lower resistance circuit through its winding 105, this circuit being traced from battery, through winding 105 and alternate contact 112 of said relay SLR², alternate contact 115 of relay AR', sleeve contacts of plug AP' and jack MJ², to ground through the winding of cut-off relay CO². The high resistance winding 106 of relay SLR² is shunted by the circuit just traced, and by this arrangement secret service is provided, 70 since a relay SLR² of a second cord circuit will not operate in series with the relay CO² as the shunt of the low resistance winding 105 of the relay SLR² of the first cord circuit renders the relay SLR² of the second 75 cord circuit inoperative, thus preventing the operator's telephone set from being connected to the second cord circuit.
- When relay SLR² of cord circuit C' energized, a circuit was closed for the relay 80 OR', which relay operates to connect the operator's telephone set in circuit with the calling subscriber's line, said circuit being traced from battery, through the winding of relay OR', alternate contact 111 of relay 85 SLR², conductor 117, normal contact 118 of relay CSR to ground. The operator's telephone set O' is now connected to the talking conductors of the cord circuit C', through alternate contacts 120 and 121 of relay OR', 90 conductors 122 and 123, normal contacts 124 and 125 of relay CSR and conductors 126 and 127. The operator now inquires the wants of the calling subscriber at the substation D, and assuming that the subscriber 95 at substation E is wanted, the operator will make the usual well-known test to determine the idle or busy condition of the called subscriber's line, and assuming that said line tests idle, the operator will insert the 100 calling plug CP' into the jack MJ², thereby closing a series circuit for the calling sleeve relay CSR and cut-off relay CO³, said circuit being traced from battery, through the winding of the relay CSR, 105 sleeve contacts of plug CP' and jack MJ², winding of cut-off relay CO³ to ground. Relay CO³ operating over this circuit removes the relay LR³ from the control of the 110 called subscriber at substation E to prevent the lighting of the line lamp signals S³, and relay CSR energizing opens its normal contacts 124 and 125 to disconnect the operator's telephone set O' from the cord circuit C'. The operator will now depress the proper ringing key plunger of the party line ringing key RK' to its fully depressed position to close the end spring contact 128 and to connect the proper frequency ringing generator G⁴, G⁵, G⁶ or G⁷ to signal the 115 called-for subscriber at substation E. The closing of alternate contact 128 of the end spring brings about the energization of the interrupter relay IR' during the interval that the key is held in its fully depressed 120 position, over a circuit traced from battery, through the lower winding of relay IR', alternate contact 128 of the end spring, conductor 129, alternate contact 113 of relay 125 SLR², conductor 130, alternate contact 118 of

relay CSR to ground. The closing of alternate contact 131 of relay IR' connects ringing current from the generator G⁵, which we will assume is the generator selected to ring the call bell of the subscriber at substation E, giving an instantaneous first ring to the called subscriber's bell. The closing of alternate contact 134 of relay IR' closes an energizing circuit for the ringing control relay RC', traced from battery, winding of relay RC', conductor 135, alternate contact 134 of relay IR', conductors 136 and 129, alternate contact 113 of relay SLR², conductor 130 to ground at alternate contact 118 of relay CSR. Relay RC' energizing over this circuit establishes a locking circuit for itself through its alternate contact 137, conductor 141, normal contact 142 of relay CS', conductor 129 and over the remainder of the previously traced circuit. Relay RC' having operated, an interrupter device I' is connected in circuit with the upper winding of the interrupter relay IR', whereby said relay IR' is caused to energize and de-energize to intermittently apply ringing current to the called subscriber's line, said circuit being traced from battery, through the upper winding of relay IR', alternate contact 138 of relay RC', to ground through the constantly rotating interrupter device I'. The called-for subscriber is now intermittently signaled.

Should the operator fail to depress the plunger of the ringing key RK' upon the insertion of plug CP' into the jack MJ³, relays IR' and RC' will not operate and a circuit will be established for the lamp signal SL', traced from the battery, through the lamp SL', normal contact 137 of relay RC', conductor 141, normal contact 142 of relay CS', conductor 129, alternate contact 113 of relay SLR², conductor 130, to ground at alternate contact 118 of relay CSR. Lamp SL' will light over this circuit to notify the operator that she has not operated her ringing key to signal the called subscriber.

Should the calling subscriber at substation D replace his receiver upon its switchhook before the called subscriber answers, ringing current will be automatically disconnected from the called line due to the fact that when subscriber D replaces his receiver relay AR' will de-energize to cause relay SLR² to de-energize, which relay SLR² de-energizing opens the locking circuit of relay RC' at its alternate contact 113, causing said relay RC' to de-energize to open the circuit of relay IR' at alternate contact 138 of relay RC', but assuming that the subscriber D does not replace his receiver but that the called subscriber E removes his receiver to answer the call during a silent or non-ringing period, that is, when relay IR' is in its de-energized position, a circuit will be closed for relay CS' to cause the same to operate

to prevent the further application of ringing current to the called line, said circuit being traced from battery, through the lower winding of relay CS', normal contact 132 of relay IR', ring contacts of plug CP' and jack MJ³, through the now closed switchhook contacts of substation E, tip contacts of jack MJ³ and plug CP', normal contact 131 of relay IR', alternate contact 145 of relay CSR, to ground through the upper winding of relay CS'. Said relay CS' operating over this circuit opens the holding circuit of the ringing control relay RC' at its normally closed contact 142, whereupon relay RC' de-energizes to open the circuit of relay IR' at contact 138 of said relay RC'. Relay CS' will not operate when in series circuit with the call bell and condenser at substation E, due to the combined high resistances of said call bell and condenser, but will energize when the receiver switchhook thereat is raised to close a shunting circuit about said call bell and condenser. Should the called subscriber remove his receiver during a ringing period, nothing will happen, since at this time relay IR' will be energized and the normally closed contacts 131 and 132 in the circuit of relay CS' will be open, but just as soon as the relay IR' de-energizes, relay CS' will energize as before described. The ringing current for operating the call bell of the called subscriber's substation E may be traced from ground through the generator G⁵ (since we have assumed that generator G⁵ is the proper generator), closed contact of the ringing key RK', conductor 146, alternate contact 131 of relay IR', tip contacts of plug CP' and jack MJ³, condenser and call bell of substation E, ring contacts of jack MJ³ and plug CP' to ground at alternate contact 132 of relay IR'. A reverting tone is transmitted to the calling substation D to notify the subscriber thereat that the called-for subscriber is being signaled, this circuit for the reverting tone being traced from ground, through the generator G⁴, condenser C, alternate contact 133 of relay IR', conductor 147, alternate contact 140 of relay RC', alternate contact 110, of relay SLR², tip contacts of plug AP' and jack MJ², through the receiver of the substation D, ring contacts of jack MJ² and plug AP', alternate contact 114 of relay SLR², lower winding of relay AR' to battery and ground.

The called and calling subscribers are now in conversational circuit, the talking circuit being traced over the heavily marked conductors. After the subscribers have finished conversation, they replace their receivers upon their respective switchhooks, causing the relays AR' and CS' to restore, due to the opening of the switchhook contacts at the respective substations. Relay AR' de-en-

ergizing opens its alternate contact 115, thereby opening the holding circuit of relay SLR^2 , which relay SLR^2 restores to disassociate the cord circuit C' from the calling subscriber's line so that the subscriber at substation D may initiate a new call and light the line lamp signals S^2 even though the plug AP' remains in the jack MJ^2 . Relay CS' restoring closes its normal contact 143, which in turn closes a circuit for the lamp signal SL' , traced from battery, through the lamp SL' , normal contact 137 of relay RC' , conductor 141, normal contact 143 of relay CS' , normal contact 113 of relay SLR^2 , conductor 130, to ground at alternate contact 118 of relay CSR . The closure of alternate contact 131 of relay IR' connects ringing current from generator G^5 , which we will assume is the one selected to ring the call bell of the called substation, giving an instantaneous first ring to the called subscriber's call bell, as before described. When relay IR' energizes, a circuit is closed for the ringing control relay RC' , traced from battery, through the winding of said relay RC' , conductor 135, alternate contact 134 of relay IR' , conductor 136, normal contacts 142 and 143 of relay CS' , normal contact 113 of relay SLR^2 , conductor 130 and to ground at alternate contact 118 of relay CSR . Said relay RC' operates over this circuit to connect the interrupter device I' in circuit with the upper winding of relay IR' to cause the same to operate intermittently to ring the called subscriber, as described in the foregoing description. Relay RC' also closes a locking circuit for itself, traced from battery through its winding and alternate contact 137, conductor 141, normal contact 143 of relay CS' , and over the previously traced circuit. Should the operator fail to depress the ringing key RK' , the lamp signal SL' will light over a circuit traced from battery through said lamp SL' , normal contact 137 of relay RC' , conductor 141, normal contact 143 of relay CS' , normal contact 113 of relay SLR^2 , conductor 130, to ground at alternate contact 118 of relay CSR ; this lamp SL' burning at this time notifies the operator that the ringing key has not been operated.

Assuming now that the calling subscriber has initiated a call and that the operator at cord circuit C' has answered the same in the manner described above, and that the subscriber wanted by the calling subscriber at substation D is the subscriber SS' which is on the same line with substation D, but only indicated on the drawing by the conductors 102' and 103' which are tied to the telephone line conductors 102 and 103 respectively, said conductors 102' and 103' extending to the substation of the subscriber SS' , the operator will notify the calling subscriber of this fact and request him to hang up his receiver while she rings the called-for subscriber. The operator at cord circuit C' will withdraw the answering plug AP' from the jack MJ^2 , and will then insert the calling plug CP' into the jack MJ^2 , thus completing a series circuit for the calling sleeve relay CSR , traced from battery through the winding of said relay CSR , sleeve contacts of plug CP' and jack MJ^2 , to ground through the winding of cut-off relay CO^2 . Relay CO^2 will operate over this circuit to prevent the lighting of the line lamp signals S^2 ; and relay CSR will also energize. The operator will now depress the proper ringing key plunger of the ringing key RK' to its maximum position to close alternate contact 128 of the end spring of said ringing key, there-

by closing a circuit for the interrupter relay IR' , traced from battery, lower winding of relay IR' , alternate contact 128 of the end spring of key RK' , normal contacts 142 and 143 of relay CS' , normal contact 113 of relay SLR^2 , conductor 130, to ground at alternate contact 118 of relay CSR . The closure of alternate contact 131 of relay IR' connects ringing current from generator G^5 , which we will assume is the one selected to ring the call bell of the called substation, giving an instantaneous first ring to the called subscriber's call bell, as before described. When relay IR' energizes, a circuit is closed for the ringing control relay RC' , traced from battery, through the winding of said relay RC' , conductor 135, alternate contact 134 of relay IR' , conductor 136, normal contacts 142 and 143 of relay CS' , normal contact 113 of relay SLR^2 , conductor 130 and to ground at alternate contact 118 of relay CSR . Said relay RC' operates over this circuit to connect the interrupter device I' in circuit with the upper winding of relay IR' to cause the same to operate intermittently to ring the called subscriber, as described in the foregoing description. Relay RC' also closes a locking circuit for itself, traced from battery through its winding and alternate contact 137, conductor 141, normal contact 143 of relay CS' , and over the previously traced circuit. Should the operator fail to depress the ringing key RK' , the lamp signal SL' will light over a circuit traced from battery through said lamp SL' , normal contact 137 of relay RC' , conductor 141, normal contact 143 of relay CS' , normal contact 113 of relay SLR^2 , conductor 130, to ground at alternate contact 118 of relay CSR ; this lamp SL' burning at this time notifies the operator that the ringing key has not been operated.

The called-for subscriber is now being intermittently signaled, and should the called subscriber answer during a non-ringing period the relay CS' will energize to prevent the further application of ringing current, or should said subscriber answer during a ringing period, relay CS' will not energize until after relay IR' has de-energized. This part of the operation of the system will be clearly understood from the foregoing description and a repetition of the same is not deemed necessary.

After a reasonable time has elapsed in which the called subscriber may be signaled, the calling subscriber will again remove his receiver and the two subscribers will then be able to converse with each other. After conversation has terminated, the subscribers will replace their receivers upon their respective switchhooks, thereby opening the circuit for relay CS' , whereupon relay CS' restores to close its normal contact 143 in the circuit of the lamp signal SL' , which lamp SL' will light, and at this time serves as a signal for

disconnection. Should either the calling or called subscriber desire to recall, he may obtain the attention of the operator at cord circuit C' by winking his switchhook, which 5 will open and close a circuit through the relay CS' to cause said relay CS' to energize and de-energize to open and close its normal contact 143 in the circuit of the lamp signal SL', thus causing the lamp signal 10 SL' to flash, which will notify the operator that her attention is desired, and she will then proceed to answer the call in the same manner as before described.

While I have illustrated and described a 15 particular embodiment of my invention, it is to be understood that I do not intend to be limited to the particular structure which is herein described and illustrated, but intend to cover all such changes and modifications 20 as come within the spirit and scope of the appended claims.

Having described my invention what I 25 claim as new and desire to secure by Letters Patent is:

1. In a telephone system including only 30 telephone lines, link circuits for interconnecting the same, said link circuits provided with automatic listening means, automatic instantaneous ringing means operable at regular intervals after said instantaneous ringing, secret service means, and a pair of link disconnect relays for controlling contacts during the completion of a connection and during conversation comprising means 35 operable by subscribers interconnected by one of said link circuits upon termination of conversation and inoperable when only one end of one of said link circuits is used in interconnecting subscribers on the same 40 line.

2. In a telephone system including subscribers' telephone lines, operator's link circuits for interconnecting said lines, a combined sleeve and link disconnect relay for 45 closing contacts in the talking conductors of a link circuit when said link circuit is connected to a subscriber's line, and automatic means controlled over said subscribers' lines to cause said relay to operate to operatively 50 disassociate said link circuit from said subscriber's line, said means inoperable to operate said relay to disassociate said link circuit and subscriber's line when only one end of said link circuit is used.

3. In a telephone system including a calling and a called subscriber's telephone line, a cord circuit for interconnecting said telephone lines in conversational circuit, a pair of combined sleeve and link disconnect relays for closing contacts in the talking conductors of said cord circuit and also for disassociating said cord circuit and said telephone lines when both subscribers hang up their receivers but inoperable if the called 60 subscriber is on the same line with the call-

ing subscriber, and a supervisory signal for signaling a disconnection.

4. In a telephone system including a calling and a called subscriber's telephone line, a link circuit for interconnecting the same, 70 a pair of combined sleeve and link disconnect relays for controlling contacts during the completion of a connection and during conversation, said pair of relays operable when both subscribers have replaced their 75 receivers upon their switchhooks to disassociate said subscribers' telephone lines and said link circuit, automatic ringing means for signaling the called subscriber, and a supervisory lamp for indicating whether or 80 not ringing current is being applied to the called line, said lamp also indicating the termination of conversation.

5. In a telephone system including subscribers' telephone lines, link circuits for interconnecting said lines in conversational circuit, a double-wound combined sleeve and link disconnect relay individual to said link circuits and adapted to be energized when a link circuit is connected to one of said telephone lines to operatively associate said connected link circuit and said telephone line, means for preventing more than one of said link circuits from being operatively connected to the same line at the same time, automatic ringing means for said link circuit for applying ringing current to the called subscriber's line, automatic means for disconnecting ringing current from the called subscriber's line when the called subscriber 90 answers or the calling subscriber replaces his receiver upon its switchhook, means for automatically operating said relay when the calling subscriber hangs up his receiver to operatively disassociate said link circuit and 95 said calling subscriber's line, and a supervisory lamp effaced when ringing current is applied to a called subscriber's line to provide a dark key shelf and operated to indicate the termination of conversation. 100

6. In a telephone system including telephone lines, link circuits for interconnecting said lines in conversational circuit, a pair of combined sleeve and link disconnect relays individual to said link circuits and 110 operable when connection is made with said lines to control contacts in said connected link circuit, energizing circuits for said relays, a third relay for controlling the energizing circuits of said pair of relays, and an energizing circuit for said third relay controlled jointly over the calling and called subscribers' lines, said third relay operating to cause the restoration of said pair of relays to operatively disassociate the calling 120 and called subscribers' lines from said connected link circuit.

7. In a telephone system including a calling and a called subscriber's telephone line, a link circuit for interconnecting the same, 130

- said link circuit having automatic listening, secret service, a counting magnet, and automatic ringing means, a pair of combined sleeve and link disconnect relays for said 5 link circuit, circuits for said pair of relays, a third relay for controlling contacts in said circuits, said third relay operable only when the receivers at the calling and called substations are in their normal positions to 10 effect operation of said pair of relays whereby said calling and called telephone lines are freed from said link circuit.
8. In a telephone system including telephone lines, a plurality of link circuits for 15 interconnecting said lines, a combined sleeve and link disconnect relay individual to said link circuits, and operable when its associated link circuit is connected to one of said telephone lines to operatively connect 20 said connected link circuit to said telephone line, a relay controlled over the calling subscriber's line, said second relay controlling the restoration of said combined sleeve and link disconnect relay whereby said calling 25 subscriber's line is operatively freed from said link circuit although a physical connection remains between said line and said link circuit, and a supervisory signal controlled jointly by the calling and called subscribers 30 for notifying the operator when conversation has terminated.
9. In a telephone system including subscribers' telephone lines, link circuits for interconnecting said lines in conversational 35 circuit, automatic ringing means for ringing the called subscriber, a combined sleeve and link disconnect relay individual to the answering and calling ends of said link circuits and operable when its associated link 40 circuit is connected to said subscriber's lines, a third relay controlled jointly by the calling and called subscribers, said third relay controlling the operation of said combined sleeve and link disconnect relays whereby 45 the calling and called subscribers' lines are operative disassociated from said link circuit, said link disconnect relays inoperable to disconnect the subscriber's line from the link circuit when both the calling and called 50 subscribers are on the same line.
10. In a telephone system including subscribers' telephone lines, a plurality of link circuits for interconnecting such telephone lines, automatic link disconnect means individual to said link circuits and operable when a link circuit is connected to different subscribers' lines, said means operable for controlling contacts to complete the connection and during conversation, automatic 55 means controlled jointly by the calling and called subscribers for causing the restoration of the link disconnect means in said link circuit whereby said link circuit and subscribers' lines are operatively dissociated from each other, and means for preventing the operation of said link disconnect means to disassociate said link circuit and subscriber's line when both the calling and called subscribers are on the same line. 60
11. In a telephone system including subscribers' telephone lines, link circuits for interconnecting said telephone lines in conversational circuit, automatic means operable to control contacts to complete a connection and for maintaining the same during conversa- 65 70 tion, said means also operable to disassociate a connected link circuit and a calling and called subscriber's line when said subscribers are on different lines but inoperable if said subscribers are on the same line. 75
12. In a telephone system including subscribers' telephone lines, link circuits for interconnecting the same, automatic ringing means for signaling a called subscriber on a line other than that of the calling subscriber or for ringing a subscriber on the same line with the calling subscriber, link disconnect means individual to said link circuits and operable to control contacts to complete a connection and to maintain the same 80 during conversation and also operable to disassociate a connected link circuit from calling and called subscriber's lines when said subscribers are on different lines but inoperable if the subscribers are on the same line. 90
- Signed by me at Chicago, in the county of Cook and State of Illinois, this 14th day of September, 1922. 95

ELMER W. LINCOLN.
